UNITED STATES PATENT OFFICE.

WALTER B. STRICKLER, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed October 15, 1920. Serial No. 417,209.

To all whom it may concern:

Be it known that I, WALTER B. STRICKLER, a citizen of the United States, residing at East Orange, in the county of Essex, State of New Jersey, have invented certain new and useful Improvements in Telephone-Exchange Systems, of which the following is a full, clear, concise, and exact description.

10 This invention relates to telephone exchange systems and particularly to cord and trunk circuit arrangements for use at a manual private branch exchange for the purpose of interconnecting subscribers' lines terminating thereat with subscribers of a main automatic exchange.

It has been the usual practice in such systems to provide each operator of the private branch exchange with an impulse sender by 20 means of which, on outgoing calls to the main automatic exchange, the setting of switches at said main exchange are controlled. Various ways of associating the impulse sender with the cord circuit have 25 been provided, one of which consisted of a key which upon actuation served to disconnect the answering end of the cord circuit from the calling end and to connect the impulse sender to the calling end. If the 30 operator failed to restore the key after completion of the impulse sender operation, and the called subscriber responded, it was impossible for the calling and called subscribers to converse due to the answering and calling end of the cord circuit being severed.

It is the object of the present invention to obviate this difficulty by providing a key for each cord circuit which, upon actuation, 40 serves to connect the operator's telephone set to the answering and calling ends of the cord circuit and to associate the impulse sender with the calling end of the cord circuit when the impulse sender is actuated. 45 The operator, having ascertained the number of the station at the automatic exchange desired by the calling subscriber, inserts the calling end of the cord circuit into an idle trunk circuit extending from the private 50 branch to the automatic exchange. The operator then actuates the impulse sender. Upon the initial actuation of the impulse sender, the talking conductors of the cord circuit are rendered discontinuous and the

interrupting contacts of the impulse sender 55 are connected to the calling end of the cord circuit. If the operator fails to restore the key, after having completed the impulse sending operation, a talking path for the calling and called subscribers independent 60 of the normal talking path of the cord circuit and common to the operator's position is provided.

Another object of the invention is to provide in a repeating trunk circuit, means for 65 preventing the false operation of switches, when a cord circuit is connected to the trunk circuit for the purpose of enabling the operator of the private branch exchange to control the setting of the switches at the 70 automatic exchange.

To attain one of the objects of the invention an inductive path normally disconnected from the cord circuits of the position and common thereto is connected in operative relationship with the answering and calling ends of a cord circuit after the listening key and impulse sender have been 75 operated. Restoring the listening key to normal removes the inductive path and the impulse sender from operative relationship with the cord circuit, whereupon they are available for use with another cord circuit.

To accomplish another object of the invention, a relay connected to one of the talking conductors of the inner section of the repeating trunk circuit, prevents the closure of a bridge across the outer section of the repeating trunk circuit until the plug of the cord circuit is fully inserted into the jack 80 of the trunk circuit.

For a more complete understanding of this invention reference may be had to the following description in connection with the accompanying drawings in which Fig. 1 95 when placed to the left of Fig. 2 shows a system containing an embodiment of the invention. Fig. 3 shows a modified form of an embodiment of the invention relating to the cord circuit.

Referring to Fig. 1 of the drawings, there is shown a common battery station A, which may be of any well-known type, having associated therewith a line jack 3, a line relay 1, and a line signal 2. The operator's 100 cord circuit O is adapted for use for either connecting two manual lines terminating at the private exchange or for connecting a 105

manual line with the automatic exchange. This cord circuit comprises the usual answering and calling plugs 4 and 23, normally connected together through the repeating coil 5. The cord circuit O is provided with supervisory relays 6 and 12, and supervisory lamps 7 and 27 connected in a manner well-known in the art, for the purpose of providing supervision in interconnecting lines 5 terminating in the branch exchange. When the cord circuit is used for interconnecting a manual line with a subscriber in the automatic exchange, lamp 7 serves as a supervisory signal and lamp 27 as a recall signal. 10 The cord circuit O is provided with the usual ringing keys 10 and 14. An answering key K is provided for the purpose of connecting the operator's talking set (not shown) with the cord circuit O. This key when actuated 15 performs the additional function of associating the impulse sender S with the cord circuit, when the cord circuit is utilized for interconnecting a line terminating at the branch exchange with the trunk circuit T 20 (shown in Fig. 2) extending to the automatic exchange. The impulse sender S, the relays 15 and 18, resistance 19, coil 20 and condensers 16 and 17 are common to the operator's position, whereas the relay 22, 25 which serves to disconnect the answering from the calling end of the cord circuit O during the sending of impulses, is individual to each cord circuit of the operator's position. Relays 15 and 18 are energized each 30 time the sender S is actuated and deenergized each time the sender S returns to normal. Relay 22 which when operated serves to disconnect the answering from the calling end, is energized upon the initial actuation 35 of sender S, and remains energized until the listening key K is restored to normal. If the operator fails to restore the listening key as soon as the impulse sending operation is completed and the called subscriber 40 responds, a talking circuit is provided for the calling and called subscribers through the inductive path including the condensers 16 and 17, said path being independent of the normal talking path and common to all the 45 cord circuits of the position.

Referring to Fig. 2 of the drawings, there is shown a trunk circuit T which is of the two-way type and terminates at one end in a jack 24 at the operator's position. Associated with the jack of the trunk circuit is a busy signal 56. The jack and signal may be multiplied to other operator's positions if the capacity of the branch exchange is such as to require the services of more than one operator. In such a case, the resistance 57 shown 55 in series with the busy signal 56 may be replaced by other busy signals. The lamp 53 serves as a calling signal on incoming calls over the trunk circuit. The other end of 60 the trunk circuit T terminates in a non-nu-

merical switch N, only the brushes of which are shown, which may be a line finder of any well-known type which operates upon the closure of a loop to connect a connector such as C with the trunk circuit. Only the line 70 relays of the connector C are shown, and the brushes of said connector are shown in connection with a called station B of the automatic exchange. The line finder N is shown multiplied to contacts in a bank of another connector switch C¹ and only so much of said connector C¹, has been shown as to illustrate how the trunk circuit T operates on incoming calls from the automatic exchange. A complete disclosure of the automatic system is not deemed necessary since it may be of any well-known type such as for example, that shown in Patent 1,231,013 of June 26th, 1917, to C. L. Goodrum.

Referring to Fig. 3 of the drawings there is shown a calling substation E at the manual private branch exchange, apparatus of trunk circuit T¹, which is located at the private branch exchange and a cord circuit D which may be used in interconnecting subscribers' lines such as E at the manual private branch exchange or in interconnecting subscribers of the manual exchange with the trunk circuit T¹.

The cord circuit D is provided with the usual supervisory relays 105 and 123 and the supervisory lamps 107 and 124 for the purpose of providing supervision for the operator in interconnecting lines of the private branch exchange. In interconnecting a subscriber of the private branch exchange with the central office over the trunk circuit T¹, lamp 107 serves as a supervisory signal and lamp 124 as a recall signal. The cord circuit D is provided with the usual ringing keys 108 and 125. An answering or listening key K¹ is provided for the purpose of connecting the operator's talking set, not shown, with the cord circuit. This key when actuated 100 performs the additional function of associating the impulse sender S¹ with the cord circuit when the cord circuit is utilized for interconnecting a line terminating at the branch exchange with a trunk circuit T¹ extending to the automatic exchange. The 105 impulse sender S¹, a set of relays whose function will hereafter be explained, a repeating coil R and condensers 115 and 116 are common to the operator's position. If the operator fails to restore the key after 110 having completed the impulse sending operation, an inductive path for conversational purposes for the calling and called subscriber is provided through the repeating coil R and the condensers 115 and 116.

The trunk circuit is of the two-way type and terminates in a jack 127 at the operator's position. This trunk circuit may terminate in a line finder switch at an automatic exchange in a manner similar to that 130

shown for the trunk circuit T in Fig. 2 of the drawings. On incoming calls over the trunk circuit T¹, ringing current responsive relay 130 is energized, thereby causing energization of trunk signal 129. When the operator answers by inserting a plug such as 126 into jack 127, the ringing current responsive relay 130 is disconnected from the jack, thereby extinguishing the trunk signal 129.

Referring to Figs. 1 and 2 of the drawings and assuming that the subscriber of station A has removed the receiver from its switchhook for the purpose of calling a subscriber at station B, at the automatic exchange, line relay 1 will be energized over a path extending from ground, upper normal contacts of jack 3, through the substation loop, lower normal contacts of jack 3, and through the winding of relay 1 to grounded battery. Line relay 1 is thereupon energized and at its armature and front contact, completes a circuit for line signal 2.

The operator noting signal 2, inserts plug 4 of the cord circuit O into jack 3 of the calling line. Insertion of plug 4 into jack 3 disconnects line relay 1 from the calling line resulting in the extinguishment of line signal 2 and the energization of supervisory relay 6 associated with the answering end of the cord circuit O. Supervisory lamp 7 of cord circuit O is prevented from lighting through the energization of relay 6 in the well-known manner.

The operator may then actuate the talking and dialing key K for the purpose of inquiring the wants of the calling subscriber. Having ascertained that station B at the automatic exchange is desired, the operator will then select an idle trunk circuit, such as T, which terminates in a jack 24 at her position and extends to the automatic exchange. Insertion of plug 23 into jack 24, completes a circuit for relay 66 over a path extending from grounded battery, winding of relay 66, tips of jack 24 and plug 23, upper normal contacts of relay 22, upper normal contacts of ringing key 14, upper right-hand winding of the repeating coil 5 to ground, and a circuit for relay 51, over a path extending from ground, left-hand normal contacts of relay 52, winding of relay 51, rings of jack 24 and plug 23, lower normal contacts of relay 22, lower normal contacts of ringing key 14, winding of supervisory relay 12, and lower right-hand winding of repeating coil 5 to grounded battery. Relay 51 thereupon operates and completes a circuit for relay 50 over a path extending from ground, upper right-hand winding of repeating coil 5, upper normal contacts of ringing key 14, upper normal contacts of relay 22, tips of plug 23 and jack 24, winding of relay 50 armature and front contact of relay 51, inner

right-hand normal contacts of relay 55, rings of jack 24 and plug 23, lower normal contacts of relay 22 and key 14, winding of supervisory relay 12, and lower right-hand winding of repeating coil 5 to grounded battery. Relay 50 in operating completes a circuit for slow-to-operate relay 58, over a path extending from grounded battery, front contact and armature of relay 50, winding of relay 58, and front contact and inner armature of relay 66 to ground. Relay 58 in operating completes a circuit for relay 54 over a path extending from ground, front contact and outer armature of relay 58, right- and left-hand windings of relay 54 in series, sleeves of jack 24 and plug 23, resistance 26, and thence in parallel, one path extending through resistance 25 and armature and front contact of supervisory relay 12 to grounded battery and the other path through lamp 27 to grounded battery. Lamp 27 is thus shunted and prevented from lighting. Relay 58 in operating also completes a circuit for relay 59 over a path extending from grounded battery, winding of relay 59, inner armature and front contact of relay 58 and front contact and inner armature of relay 66 to ground. Relay 59 in operating renders the talking conductors of the trunk T continuous. Relay 54 in operating locks up through its inner armature to ground. Relay 54 in operating also completes a circuit through its outer armature and front contact for relay 55. The busy signal 56 is energized when relay 52 releases by a circuit including the front contact and outer left-hand armature of relay 55, and armature and front contact of relay 50.

In case the tip and ring of jack 24 is short circuited by the tip of the plug 23 of the cord circuit when plug 23 is being inserted into jack 24 of the trunk current T, relays 51 and 66 will operate in series over a path extending from grounded battery, winding of relay 66, tip and ring of jack 24, (which have been assumed to be short-circuited by the tip of the plug 23) and winding of relay 51 to ground. Relay 66 in operating connects ground to the winding of relay 58, and relay 51, in operating bridges relay 50 across the tip and ring conductors of the inner section of the trunk over a path extending from tip conductor of the inner section of the trunk T, winding of relay 50, armature and front contact of relay 51, back contact and inner right-hand armature of relay 55 to the ring conductor of the inner section of the trunk T. Relay 50 will not operate at this time however due to the short-circuit across the tip and ring of the jack 24 of the trunk circuit T. Therefore, relay 58 will operate and the bridge will not be closed across the outer section of the trunk, since relay 50 controls

the successive energization of relays 58, 54 and 55, the latter of which causes the bridge to be placed across the outer section of the trunk. It is thus seen that the outer section of the trunk is not bridged to cause the operation of the switches at the automatic exchange until the plug 23 is fully inserted in the jack 24.

As soon as the plug 23 is fully inserted 10 into jack 24 relays 66, 51, 50, 58, 54, 59 and 55 are operated as heretofore described, and the circuit is in condition for sending impulses. Upon the initial movement of the impulse sender or dial S from normal position, relay 15 is operated over a circuit extending from ground, contacts 40 of dial S and winding of relay 15 to grounded battery. Relay 15 in operating, completes a circuit at its front contact and lower, inner 20 armature for relay 18, and opens at its outer, lower armature and back contact, the circuit leading to the operator's telephone set. Relay 18 in operating completes a circuit for relay 22 over a path extending from 25 grounded battery, winding of relay 22, contacts 42 of key K, front contact and upper armature of relay 18 to ground. Relay 22 is thereupon energized and locks up over a path extending from grounded battery, 30 winding of relay 22, contacts 42 of key K and outer, lower armature and front contacts of relay 22 to ground. Relay 22 in operating connects the impulse springs 41 of the dial S to the tip and ring conductors of the 35 calling end of the cord circuit O and disconnects the answering end from the calling end. Each time the dial S returns to normal position, relays 15 and 18 are de-energized. In returning to normal position, 40 the contact 41 of the dial S will be opened a number of times corresponding to the digit dialed. In response to the impulses transmitted from the dial S, impulse relay 66 of the trunk circuit T will be intermittently energized and deenergized over a path 45 extending from grounded battery, winding of relay 66, tips of jack 24 and plug 23, upper alternate contacts of relay 22, lower alternate contacts of relay 18, resistance 19, 50 contact 41 of dial S, inner, lower alternate contacts of relay 22, jack 23 and plug 24 and winding of relay 51 to ground. At the first release of relay 66, in response to the first impulse transmitted thereto, relays 58 55 and 59 release. The function of relay 59 in releasing during the transmission of impulses is to short-circuit the retardation coil 61, resistance coil 60, and relay 65 as well to open the incoming end of the trunk circuit. Relay 52 is preferably of the slow-to-operate type in order to prevent flashing of the supervisory lamp in case of a 60 momentary operation of relay 65 during the transmission of impulses. Relay 58 is preferably slow-to-operate in order to prevent

operation of relay 59 during the transmission of impulses. Relay 64 is of the slow-to-release type and remains operated during the impulse sending period.

In accordance with each impulse transmitted from the dial S, impulses are repeated to an impulse relay such as 79 associated with an automatic switch at the automatic exchange over a path extending from ground, left-hand winding of relay 79, brush 75 1, terminal 68, conductor 99, outer-right-hand armature and front contact of relay 55, outer armature and front contact of relay 66, upper normal contacts of relay 59, conductor 98, terminal 70, and right-hand winding of relay 79 to grounded battery. After having sent a sufficient number of impulses to set the connector switch upon the terminals of the desired station B, the operator may restore the key K to normal position. Station B may then be signaled in the well-known manner. When the called subscriber responds, talking battery will be supplied to his station from a relay 85. The calling subscriber A will be supplied with talking 90 battery through the windings of repeating coil 5 of the cord circuit O. If the operator fails to restore the key K to normal after dialing, a talking circuit, independent of the normal talking conductors of the cord circuit O and common to the cord circuits of the operator's position, is available, said talking circuit including the upper and intermediate contacts of relay 22, condensers 16 and 17, outer and inner upper contacts of 95 relay 15 and upper and intermediate contacts of key K. The operator's telephone circuit (not shown) is bridged across this circuit and when conversation over the trunk circuit commences, the operator will be able to hear either party talking so that she is thereby audibly informed that she has failed to restore the key K to normal position. The operator, hearing conversation, will immediately restore the key K to normal. 100 After the completion of conversation, and restoration of the receiver to the switch-hook at substation A, supervisory relay 6 of the cord circuit C will be deenergized, thereby causing the lighting of supervisory 105 lamp 7, in the well-known manner, which serves as an indication to the operator that conversation is completed. The operator may thereupon remove the plugs 4 and 23 from their associated jacks. Removal of plug 23 from jack 24 will cause the restoration of the release of the cord circuit O to normal position, thereby resulting in the interruption of the loop across the outgoing end of the trunk circuit which will cause release of the switches at the automatic exchange in the well-known manner.

On incoming calls over the trunk circuit T to the operator's position, the ringing current responsive relay 65 may be energized 110

due to the application of ringing current to the conductors 98 and 99, extending from the automatic exchange to the manual exchange. The path for the energization of relay 65 may be traced as follows: ground, side switch arm 93 in its third position, brush 87, terminal 90, conductor 98, winding of relay 65, normal contacts of relay 64, condenser 63, conductor 99, terminal 91, brush 89, side switch arm 94 in its third position, winding of relay 95, armature and front contact of relay 96, (relay 96 being operated), to a source of ringing current 97. Relay 65, in operating completes a circuit 10 at its armature and front contact for slow-to-operate relay 52. Relay 52 in operating locks up through its right-hand contact and the outer left-hand normal contacts of relay 55, and completes a circuit for line signal 20 53 and busy signal 56 over a path extending from grounded battery, right-hand armature and front contact of relay 52 and thence in parallel, one path extending through the inner, left-hand normal contact 25 of relay 55 and line lamp 53 to ground and the other through busy signal 56 and resistance 57 to ground. In place of resistance 57, a number of busy signals may appear in series with busy signal 56 at other operator's 30 position, thus indicating to such other operators that the trunk circuit, terminating in jack 24 which is multipled to other positions, is busy. Trunk signal 53 serves as an indication to the operator that a call 35 from the automatic exchange has arrived.

The operator noting the trunk signal 53, inserts plug 23 into jack 24, whereupon relay 54 is energized and locks up over a path previously described. Relay 54 in operating completes a circuit through its contacts for relay 55, which in operating, causes the release of relay 52. Relay 55 in operating, opens the circuit for trunk signal 53, thereby extinguishing said signal. The busy signal 56 is maintained energized however when relay 52 retracts its armature due to a circuit therefor being maintained through the inner, left-hand contact of relay 55. Impulse repeating relay 66 then operates over a circuit previously traced and in energizing, completes a circuit through its inner armature and front contact for relays 58 and 64 and through its outer armature and front contact places a bridge across the outgoing 50 side of the trunk circuit to trip the machine ringing. The bridged circuit may be traced as follows: from tip conductor 98 of trunk circuit T to the upper normal contacts of relay 59, front contact and outer armature of relay 66, front contact and outer armature of relay 55 to ring conductor 99.

When the machine ringing at the automatic exchange is tripped, the side switch arms are moved in the fourth position, 60 thereby placing the subscriber at the auto-

matic exchange in conversational relationship with the operator at the manual exchange. Relay 58 in operating completes a circuit for relay 59 over a path extending from grounded battery, winding of relay 59, inner left-hand armature and front contact of relay 58 and front contact and inner armature of relay 66 to ground. Relay 58 in operating also removes the short circuit from relay 51. Relay 64 in operating places relay 65 and condenser 62 in parallel with coil 61 and resistance 60 as herebefore described. When relay 59 operates, it renders the tip and ring talking conductors of the trunk circuit continuous and removes the shunt 80 from the retardation coil 61 and resistance 60. Current now flows from relay 200 of the connector switch over a path extending from ground, left-hand winding of relay 200, side switch arm 93 in its fourth position, brush 87, terminal 90, conductor 98, through resistance 60 and retardation coil 61, front contact and outer armature of relay 66, front contact and outer right-hand armature of relay 55, conductor 99, terminal 91, brush 89, side switch arm 94 in its fourth position and right-hand winding of relay 200 to grounded battery.

The operator may then actuate the talking and dialing key K for the purpose of inquiring the wants of the calling subscriber and assuming that substation A is desired, may insert the plug 4 into jack 3 and then actuate ringing key 10 to signal the desired subscriber in the well known manner. When the subscriber at the substation A responds, supervisory lamp 7 will be extinguished.

Upon completion of conversation, supervisory lamp 7 will glow, thus indicating to the operator that conversation has ceased. The operator may then remove plugs 4 and 23 from their associated jacks whereupon all apparatus will be restored to normal and the system is ready for the next call.

Referring to Fig. 3 of the drawings, it will be assumed that the subscriber of station E desires connection with a trunk circuit T¹ leading to an automatic exchange. Upon removal of the receiver from the switchhook at station E, a circuit is established for line relay 100 over path extending from grounded battery winding of relay 100, lower normal contacts of jack 102, through the substation loop and upper normal contacts of jack 102 to ground. Relay 100 is thereupon energized and completes a circuit through its armature and front contact for line lamp 101, which causes said lamp to glow and to serve as a calling signal for the calling station E.

The operator noting the signal, inserts plug 103 of the cord circuit D into jack 102, thereby causing the deenergization of line relay 100, which, in retracting its armature,

opens the circuit for line lamp 101. Insertion of plug 103 into jack 102 also completes a circuit for supervisory relay 105 of the cord circuit D, thereby preventing supervisory lamp 107 of the cord circuit D from lighting. Supervisory relay 105 is energized over path extending from ground, back contact and upper outer armature of relay 121, upper winding of retardation coil 112, upper normal contacts of relay 109, upper normal contacts of ringing key 108, tips of plug 103 and jack 102 through the substation loop, rings of jack 102 and plug 103, lower normal contacts of ringing key 108, through the winding of supervisory relay 105 and the upper and lower windings of resistance 104 in parallel to the lower normal contacts of relay 109, lower winding of retardation coil 112, back contact and upper inner armature of relay 121 to grounded battery.

The operator may then actuate the talking and dialing key K^1 thereby placing the operator's telephone set (not shown) in operative relationship with the calling station. The operator's telephone set is connected with the tip and ring conductors 198 and 199, respectively of the cord circuit over a path extending from conductor t outer normal contacts of relay 119, contacts 152 of key K^1 to the tip conductor 198 of the cord circuit and from conductor N, through the outer right-hand armature and back contact of relay 113, inner normal contacts of relay 119, contact 156 of key K^1 to the ring conductor 199 of the cord circuit. After inquiring the wants of the calling subscriber and assuming that a connection with a subscriber of the automatic exchange is desired, the operator may insert plug 126 of the cord circuit D into the jack 127 of an idle trunk such as T^1 extending to the automatic exchange. Insertion of plug 126 into jack 127 causes the operation of relay 121 over path extending from ground, winding of relay 121, sleeves of plug 126 and jack 127 and resistance 128 to grounded battery. Relay 121 is thereupon energized. In attracting its armatures, relay 121 bridges retardation coil 112 across the cord circuit D over a path extending from tip conductor 198 of the cord circuit through the upper winding of retardation coil 112, upper outer armature and front contact of relay 121, back contact of inner left-hand armature of relay 106, and lower winding of retardation coil 112, to the ring conductor 199 of the cord circuit. Relay 121 in attracting its armatures also completes a circuit for relay 106 over a path extending from grounded battery, upper inner armature and front contact of relay 121, winding of relay 106, front contact and armature of relay 105, sleeves of plug 103 and jack 102 to ground. Relay 106 in energizing, locks up through its front

contact and inner right-hand armature and through contacts 153 of key K^1 to ground at the operator's telephone set over conductor h as soon as key K^1 is restored to normal position. Relay 106 in attracting its inner left-hand armature, opens the bridge of the retardation coil 112, but the switches at the automatic exchange are operated and held by the retardation coil 120 which is bridged across the trunk circuit when the key K^1 is operated or by the subscribers' loop.

The operator may then proceed to actuate the impulse sender or dial S^1 to send impulses over the trunk circuit T^1 to the automatic exchange for the purpose of operating switches thereat. Upon the initial actuation of the dial, relay 113 is operated over path extending from ground through off normal contacts 155 of the dial S^1 and winding of relay 113 to grounded battery. Relay 113 is thereupon energized and at its right-hand contacts disconnects ring conductor N, extending to the operator's telephone set from the cord circuit and at its left-hand contacts completes a circuit for relay 114. Relay 114 thereupon energizes and at its right-hand contacts disconnects retardation coil 120 from the calling end of the cord circuit and bridges the interrupting contacts 154 of the dial S^1 across the tip and ring conductors 196 and 197, respectively of the cord circuit over path extending from conductor 197 through contacts 151 of key K^1 , right-hand alternate contacts of relay 114, contacts 154 of dial S^1 , contacts 150 of key K^1 to tip conductor 196 of the cord circuit. Relay 114 in operating also completes a circuit at its left-hand armature and front contact for relay 119, which in operating disconnects battery and ground at the automatic exchange from the calling substation and connects battery and ground thereto over a path extending from ground, upper winding of relay 118, upper right-hand winding of repeating coil R, left-hand alternate contacts of relay 119, contacts 152 of key K^1 , tip conductor 198 of the cord circuit D, upper normal contacts of relay 109, upper normal contacts of ringing key 108, tips of plug 103 and jack 102 through the substation loop, rings of jack 102 and plug 103, lower normal contacts of ringing key 108 through the winding of relay 105 and the upper winding of resistance 104 in parallel to the lower normal contacts of relay 109, contacts 156 of key K^1 , inner alternate contacts of relay 119, lower right-hand winding of repeating coil R and lower winding of relay 118 to grounded battery. Supervisory relay 105 of the answering end of the cord circuit is thus maintained energized when the battery from the central office is disconnected from the calling substation. Relay 118 is operated over the path traced and completes

a holding circuit for relay 119. Relay 119 thus remains energized until key K^1 is restored to normal, thereby preventing clicks from being transmitted to the calling substation each time the dial returns to normal. As the dial returns to normal position, contacts 154 will be interrupted a number of times corresponding to the digits dialed. Each time the dial S^1 returns to normal position relays 113 and 114 release. In response to the interruptions caused by the dial S^1 , automatic switches at the automatic exchange may be set upon the terminals of the desired subscriber in any well-known manner.

After the dialing operation is completed, the operator may restore key K^1 to normal position, thereby establishing a talking circuit for the calling subscriber to the trunk conductors 160 and 161 of the trunk circuit T^1 over a path extending from conductor 160, tips of jack 127 and plug 126, upper normal contacts of ringing key 125, conductor 196, contacts 158 of key K^1 , conductor 198, upper normal contacts of relay 109, upper normal contacts of ringing key 108, tips of plug 103 and jack 102 through the substation loop, rings of jack 102 and plug 103, lower normal contacts of ringing key 108, thence through the upper winding of resistance 104 and relay 105 in parallel to the lower normal contacts of relay 109, contacts 159 of key K^1 , winding of relay 123, lower normal contacts of ringing key 125, rings of plug 126 and jack 127 to trunk conductor 161. Restoration of key K^1 to normal position completes a locking circuit of relay 106 heretofore traced, and causes the release of relays 118 and 119, so that the dial may be associated with another cord circuit at the operator's position.

If the operator fails to restore the key K^1 to normal after dialing, a talking path, independent of the normally continuous talking conductors, will be provided through the repeating coil R which is common to the position, said path including contacts 150, 152, 156 and 151 of key K^1 , right and left hand windings of repeating coil R , condensers 115 and 116, winding of relay 118 and alternate contacts of relay 119. The operator's telephone set is, at this time, connected across this circuit and the operator may thus be audibly informed, when conversation commences, that she has failed to restore the key to normal. The operator, hearing the conversation, may then restore key K^1 to normal position.

Upon completion of conversation and restoration of the receiver to the switchhook at substation E, supervisory relay 105 will be deprived of current thereby causing the release of this relay and the lighting of supervisory signal 107, which serves as a disconnect signal to the operator. Relay 105 in

releasing also completes a circuit for splitting relay 109 over a path extending from ground, sleeves of jack 102 and plug 103, armature and back contact of relay 105, front contact and outer right-hand armature of relay 106, and winding of relay 109 to grounded battery. Relay 109 thereupon attracts its armatures thereby disconnecting the answering plug 103 from the calling plug 126 and connecting ground and battery to the tip and ring conductors, respectively of the answering end of the cord circuit.

The operator noting the disconnect signal 107 may remove the plugs 103 and 126 from their associated jacks, whereupon the line and trunk circuits are ready for the next call.

It will now be assumed that a call has arrived at the operator's position over trunk circuit T^1 due to a source of ringing current being applied to the trunk conductors 160 and 161. Applying ringing current to the trunk conductors 160 and 161 causes the energization of 130 over a path extending from conductor 160 upper normal contacts of jack 127, right-hand winding of relay 130, condenser 131 to conductor 161. Relay 130 in operating completes a locking circuit for itself and a circuit for the lighting of lamp 129 over a path extending from ground, armature and front contact of relay 130, through the lower normal contacts of jack 127, and thence in parallel, one path extending through lamp 129 to grounded battery and the other through the left-hand winding of relay 130 to grounded battery. The operator noting the trunk signal 129 inserts plug 126 into jack 127, whereupon the locking circuit for relay 130 is opened thereby causing the deenergization of said relay and the consequent extinguishment of trunk signal 129. Insertion of plug 126 into jack 127 also completes a circuit for relay 121 over a path extending from ground, winding of relay 121, sleeves of plug 126 and jack 127 and resistance 128 to grounded battery. Relay 121 in operating bridges retardation coil 112 across the cord circuit over a path extending from conductor 198 of the cord circuit, upper winding of retardation coil 112, upper outer armature and front contact of relay 121, back contact and inner left-hand armature of relay 106 and lower winding of retardation coil 112 to conductor 199 of the cord circuit thereby tripping ringing at the automatic exchange, if the call is from an automatic ringing source.

The operator may then actuate the key K^1 to inquire the wants of the calling subscriber and after having ascertained the station desired restores key K^1 to normal. Assuming that station E is desired, the operator inserts plug 103 into the jack 102 and

then actuates ringing key 108 to signal the station E in the well-known manner. Insertion of plug 103 in the jack 102 completes a circuit for supervisory lamp 107 over a path extending from grounded battery, through lamp 107, back contact and armature of relay 105, sleeves of plug 103 and jack 102 to ground. When the calling subscriber responds, supervisory relay 105 operates due to current flowing from the connector switch at the automatic exchange through the trunk and cord circuit and the subscriber's loop in parallel with the path through retardation coil 112. Supervisory lamp 107 is thereupon extinguished indicating to the operator that the called subscriber has responded. Relay 105 in operating also completes a circuit for relay 106 over a path extending from ground, sleeves of jack 102 and plug 103, armature and front contact of relay 105, winding of relay 106, front contact of upper inner armature of relay 121 to grounded battery. Relay 106 in operating locks up through its front contact and inner right-hand armature and contacts 153 of key K¹ to ground at the operator's telephone set. Relay 106 in operating also opens the circuit, at its back contact and inner left-hand armature, of the retardation coil bridge, and reduces the resistance of the shunt around the winding of supervisory relay 105 by short-circuiting the lower winding of resistance 104 by the closure of its outer left-hand armature and front contact. Due to the energization of relay 106, the retardation coil bridge, as before stated, is removed from the line thereby placing the connection under the control of station E.

Upon completion of conversation and restoration of the receiver to the switchhook at station E, relay 105 releases due to the opening of the direct current path at the substation, thereby closing a circuit for supervisory lamp 107. A circuit is also closed for splitting relay 109 over a path extending from grounded battery, winding of relay 109, outer right-hand armature and front contact of relay 106, back contact and armature of relay 105, sleeves of plug 103 and jack 102 to ground. Relay 109 in operating disconnects the calling from the called end of the cord circuit and connects battery and ground through its lower and upper alternate contacts, respectively, to the answering end of the cord circuit. If the operator does not immediately take down the connection and the subscriber of station E, desires to make another call, the operator may be signalled by means of the supervisory lamp 107. If, before the operator takes down the connection, a call arrives over the trunk circuit T¹, the calling station E will not be signalled, but the ringing current will pass through ringing current

responsive relay 110 and condenser 111 thereby energizing relay 110 and completing a circuit for lamp 124 over a path extending from grounded battery, through lamp 124 and front contact and armature of relay 110 to ground. Lamp 124 will be lighted each time relay 110 is energized and serves as a recall signal for the operator. The operator noting the recall signal may actuate the key K¹ and inquire the wants of the calling subscriber and then complete the connection as heretofore described.

What is claimed is:

1. In a telephone system, a cord circuit having normally continuous talking conductors terminating in an answering and a calling plug, an operator's key, an impulse sender, means responsive to the actuation of the key and the sender for rendering the talking conductors of the cord circuit discontinuous, and a talking path provided differing from the normally continuous talking conductors of the cord circuit if the operator's key is not restored to normal.

2. In a telephone system, a cord circuit having normally continuous talking conductors terminating in an answering and a calling plug, an operator's key, an impulse sender having a forward and backward movement, means responsive to the actuation of the operator's key for associating the sender with the cord circuit, means responsive to the forward movement of the sender for rendering the talking conductors of the cord circuit discontinuous, a trunk circuit connected to the calling terminal of the cord circuit terminating in an automatic switch, means responsive to the backward movement of the sender for setting the switch and a talking path provided differing from the normally continuous talking conductors of the cord circuit if the key is not restored to normal.

3. In a telephone system, a cord circuit having normally continuous talking conductors terminating in an answering and a calling plug, an operator's telephone circuit, an impulse sender having a forward and backward movement, a trunk circuit connected to the calling plug of the cord circuit and terminating in an automatic switch, an operator's key adapted upon actuation to connect the operator's telephone set to the cord circuit and to associate the impulse sender with the cord circuit, means responsive to the forward movement of the impulse sender for disconnecting the operator's telephone set from the cord circuit and for rendering the talking conductors of the cord circuit discontinuous, means responsive to the backward movement of the impulse sender for controlling the operation of the automatic switch, and means for providing a talking path through the cord

circuit if the operator's key is not restored to normal.

4. In a telephone system, a cord circuit having normally continuous talking conductors, an operator's key, an impulse sender, means responsive to the actuation of the key and sender for rendering the talking conductors discontinuous, and a talking path provided differing from the normally continuous talking conductors if the operator's key is not restored to normal.

5. In a telephone system, a cord circuit terminating in a pair of plugs, a talking circuit normally connecting said plugs, an operator's key, an impulse sender, means responsive to the successive actuation of said key and said sender for interrupting said talking circuit, and a talking circuit which is different from said normal talking circuit if said key is not restored to normal.

6. In a telephone exchange system, a plurality of cord circuits each having normally continuous talking conductors, a key for each cord circuit, an impulse sender common to said cord circuits, means responsive to the actuation of the key of a cord circuit for associating the sender therewith, means responsive to the actuation of the sender for rendering the talking conductors of the cord circuit discontinuous, and a talking path differing from the normal talking circuit if the operator's key is not restored to normal.

7. In a telephone system, an operator's position, a plurality of cord circuits thereat, an operator's key for each cord circuit, an impulse sender common to said cord circuits, means responsive to the actuation of a key for associating said sender with a cord circuit, means responsive to the actuation of the sender for disconnecting the answering from the calling end of the cord circuit, and an inductive talking path for uniting the answering and calling ends of the cord circuit immediately after said sender has been actuated.

8. In a telephone system, an operator's position, subscribers' lines and trunk lines terminating thereat, cord circuits at said position each having a key associated therewith, an impulse sender for said position, and circuit connections controlled by a key of one of said cord circuits and said impulse sender, whereby in extending a call from a subscriber's line over said trunk circuit, a talking path is provided if the operator fails to restore the key after having operated the impulse sender.

9. In a telephone system, an operator's position, subscribers' lines and trunk lines terminating therein, a plurality of cord circuits for interconnecting said subscribers' lines and trunk lines, an operator's telephone circuit at said position, a key for each cord circuit for connecting said operator's tele-

phone set to said cord circuit when answering a call, an impulse sender for said position, means including said sender for establishing a talking connection over one of said cord circuits and one of said trunk lines between two subscribers' lines, and means whereby said talking connection is maintained between said lines if the operator fails to restore the said key.

10. In a telephone system, a two-way two conductor trunk circuit terminating at one end in a jack at an operator's position and at the other end in an automatic switch, a cord circuit terminating in a plug for extending a call over said trunk circuit, a relay connected to said trunk circuit energized upon the insertion of the plug of the cord circuit into the jack of the trunk circuit, a second relay cooperating with said first mentioned relay for closing a bridge across said trunk circuit to operate said automatic switch, and means for preventing the energization of said second relay until the plug of the cord circuit has been completely inserted into the jack.

11. In a telephone system, a trunk circuit having inner and outer sections, said inner section terminating in a jack and said outer section terminating in an automatic switch, a repeating relay connected to the inner section of said trunk circuit, a second relay cooperating with said repeating relay upon energization for bridging the outer section of said trunk circuit, a cord circuit terminating in an answering and a calling plug, a circuit completed for said repeating relay when the calling plug of said cord circuit is inserted into the jack of said trunk circuit, and a third relay associated with said trunk circuit for delaying the operation of said second relay until the plug of said cord circuit is completely inserted into the jack of said trunk circuit.

12. In a telephone system, a private branch exchange, extensions leading therefrom, a trunk line extending from said exchange to a main central office, a cord circuit for establishing connections between said extensions and said trunk line, an operator's set including dialing means for controlling the operation of mechanical switches for association with said cord circuit, means whereby, when said operator's set is associated with the cord circuit and said dialing means is operated to control mechanical switches at the main central office, the end of the cord circuit associated with an extension will be disconnected from the end associated with the trunk line, and means whereby at the completion of the dialing operation, the two ends of the cord circuit may be interconnected for talking purposes through the operator's set.

13. In a telephone system, a private branch exchange, extensions leading therefrom, a

trunk line extending from said exchange to the main central office, a cord circuit for establishing connections between said extensions and said trunk line, an operator's set including dialing means for controlling mechanical switches associated with said cord circuit, means automatically responding to the operation of said dialing means to disconnect the end of the cord circuit associated with the extension from the end as-

sociated with said trunk line, and means automatically functioning, at the end of the dialing operation, to interconnect the two ends of the cord circuit through the operator's set for talking purposes.

15

In witness whereof, I hereunto subscribe my name this 13th day of October, A. D. 1920.

WALTER B. STRICKLER.
